UNITED STATES PATENT OFFICE.

LOUIS ULLMAN, OF NEW YORK, N. Y.

PLIERS AND LOCKING LUG FOR REPLACING TRANSMISSION COVERS ON FORD CARS.

1,407,362.

Specification of Letters Patent. Patented Feb. 21, 1922.

Application filed January 18, 1921. Serial No. 438,123.

To all whom it may concern:

Be it known that I, LOUIS ULLMAN, a citizen of the United States, residing at New York city, in the county of New York and State of New York, have invented certain new and useful Improvements in Pliers and Locking Lugs for Replacing Transmission Covers on Ford Cars, of which the following is a specification.

10 My invention relates generally to an improved tool for facilitating the assembling of the parts of a Ford transmission system, and it has especial reference to pliers adapted to simultaneously compress the three 15 springs forming a part of such system, and to a lock or locking lug for holding the pedals immovable while the pliers are being used on the springs.

It is a well known expedient to provide 20 means by which the triple pedal springs mounted on the pedal spindles may be compressed for the purpose of assisting in assembling a transmission case of the Ford type; and pliers have been designed to aid 25 in this work, but so far as I am aware compression pliers having jaws movable in parallel relation to each other as they approach and recede, and the combination therewith of a device for locking the pedals in a fixed 30 position to further aid in properly locating the springs before compression, are new in the art. The greatest difficulties encountered with existing devices are first, that because the jaws of the pliers, embracing the springs, 35 approach each other in an arcuate line, the springs are caused to buckle and bind against the pedal spindles; and second, that no means has been provided to hold the spindles in their extended positions during 40 the manipulation of the pliers.

Thus, inasmuch as the ease with which the springs may be moved transversely of the spindles depends upon the axis of the springs remaining straight; it will be apparent that 45 the provision of a device, which will not cause the axis of the springs to become deformed during compression, will be a decided advantage over those now in use.

With the defects of existing structures in 50 mind, the principal object of the present invention is to provide a device by means of which the springs may be compressed in a straight line and during such compression the pedals be held in locked position so as

to prevent interference with the work of 55 compressing the springs.

A further object of this invention is to provide the walls of the tool openings which span the spindles with shoulders thereby forming seats for the reception of the end 60 coils of the springs, to prevent the latter from buckling during compression of the springs. Such shoulders, when the coils are seated therein, prevent contact of the tool with the spindle, and possible injury to the 65 latter.

The invention comprises the novel features of construction, combinations, relations and arrangements of parts disclosed in 70 the following specification and fully illustrated in the accompanying drawings, wherein:

Fig. 1, is a perspective view of the cover portion of a Ford transmission case showing the triple compression pliers in operative position about the pedal springs and the pedal locking device holding the pedals against movement in either direction. 75

Fig. 2, is a fragmental plan view of the cover casing adjacent the bearings for the 80 pedal spindles, showing the cam surfaces and the locking device in its operative position.

Fig. 3, is a front elevational view of the 85 pedal locking device.

Fig. 4, is a side elevational view of the 90 triple spring compression pliers in its closed position, showing the spring compressed between the jaws.

Fig. 5, is a similar view to that shown in Fig. 4 except that the pliers are extended and the spring expanded. 95

Fig. 6, is an elevational view of the inner side of one of the clamping jaws showing the springs in the seats.

Fig. 7 is substantially a sectional view taken on the lines 7-7 of Fig. 6.

Referring to the drawings, 10 denotes the cover portion of a Ford transmission case having a suitable manhole 11. The reverse, 100 slow speed and brake pedals 12 are mounted upon spindles 13 carried transversely of the cover 10. Cam surfaces 14 provided on the hubs of the two outer pedals and on the spindle of the intermediate pedal are 105 engaged by opposed cam surfaces on the edge of the bearing bosses of the case 10. When the cams 14 are in their normal or

engaged position the outer spindles 13 extend into the case their maximum length and the intermediate spindle is moved outwardly, leaving a space between the hub of 5 the pedal thereon and the edge of the bearing boss, this space being utilized for the purpose hereinafter described. The spindles 13 are held in their respective positions by coiled springs 15 which abut against the 10 inner surfaces of the ears of the transmission bands, not shown. The normal tendency of these springs 15 is to hold the cams 14 engaged resulting in an upright position of the pedals 12.

15 In order to lock the pedals in their upright position a pedal lock is provided consisting of a flat steel member 17 having a centrally located bifurcation 18 extending from the edge thereof to a point well into 20 the body of the lock. One end of this lock 17 is provided with a button 19 having its exposed surface concaved to receive the rounded end of one of the spindles 13. The opposite end of the tool 17 carries a clamp 25 screw 20 movable transversely of said tool; and the inner end of said screw supports a swivel 21 having its outer surface concaved to provide a seat into which the end of another of the spindles 13 engages. In order 30 that the lock 17 may be easily inserted in its proper position, the outer face of the lock is chamfered so that the space between the hub of the centrally located pedal 12 and the edge of the boss forming its bearing will be 35 sufficient to permit the lock to enter the intervening space and to properly embrace the central spindle, as hereinafter described. A suitable opening may be provided in the lock 17 to receive one end of a flexible chain 22 40 having its opposite end attached to one handle of the pliers about to be described.

The pliers 23 consist primarily of the handle members 24 which are pivotally interconnected and by a pivot screw 25. Ex- 45 tending beyond their pivotal point 25 a distance considerably less than the length of the handles 24 are the rounded nose portions 26 having transversely disposed pivot pins 27, adapted to pivot between ears 28^a; said 50 ears being carried by opposed toggle jaws 28. The lower portion of each of the jaws 28 is provided with three slots 29 adapted to receive the spindles 15, and the marginal wall of each slot is provided with a shoulder 55 30 to form a seat for the end coil or coils of a spring.

The clamping toggle jaws 28 approach each other substantially parallel to the axes of the spindles 13; this movement is made 60 possible by a cam follower 31 provided at each of the opposite upper ends of the jaws 28. These followers 31 are held against cam surfaces 32 by means of a coil spring 33 having its opposite ends attached to the face of 65 the followers 31. The cam surfaces 32 are

the edges of the handles adjacent their pivot 25, and are of such curvature to permit the followers 31 to rest thereon, to approach each other when the handles are brought together. To prevent too great compression 70 of the springs 15 an adjusting screw 34 is carried on the inner edge of one of the ears of the pivots 27, and may be moved to project a greater or a lesser distance away from the ear; the screw 34 may predetermine how 75 closely the jaws may approach each other. It is desirable after compressing the springs 15 to hold them in this position until the cover 10 is properly adjusted to its place; for this purpose a hinged bolt 35 is pivoted 80 at the end of one of the handles 24 and adapted to be received by the bifurcated end 37 of the other handle member. A winged nut 36 is mounted on the free end of the hinged bolt so that it may engage over the 85 outer edge of the handle and hold the two members in a fixed closed position. The opening 38 in one of the handles 24 is provided to receive the other end of the flexible chain 22 before referred to. 90

In the manipulation of the tool constituting this invention it is necessary for the transmission bands to be held in their respective positions about the drums while the cover casing 10 is separated from the under 95 section of the transmission case. This may be done in any suitable manner, and results in bringing the openings in the two ends of each band in axial alinement and the springs 15 compressed thereby permitting the nuts 100 on the pedal spindles 13 to be readily unscrewed to release the pressure against the springs 15. The cover casing 10 may then be removed.

Assuming that the necessary repairs or 105 adjustments have been made and the transmission cover casing 10 is about to be superposed upon the under member of the casing, the necessary steps required to lock the pedal spindles 13 in fixed position and to compress 110 the springs 15 will be as follows:

Both the forward and rear pedals 12 must be moved into an upright position on the cams 14 so that the spindles 13 may be projected their greatest distance into the interior of the casing 10; the centrally located pedal having its cam movable in an opposite direction must be moved outwardly in relation to the other pedals. This presents a space between the edge of the bearing boss 120 and the inside of the pedal hub, in which space the spindle itself will be exposed. As clearly shown in Fig. 2 the lock 17 may then be placed over the exposed portion of the central spindle permitting the slot 18 to pass 125 over the latter. The stationary button 19 will seat against the protruding end of one of the spindles 13 and the swivel seat 21 will seat against the other spindle end. The locking action is then brought about by 130

tightening the clamp screw 20, which will cause an inward pressure upon the front and rear spindles thereby interlocking the cams 14, and an outward pressure upon the central spindle as the hub of its pedal is used as a stop or fulcrum for the lock 17. The 5 pedals 12 are then securely locked in their respective positions, and by a simple manipulation the springs are moved on the 10 spindles in position to have their opposite ends engaged by the plier jaws.

In Fig. 5 the handles 24 are shown separated and the clamping jaws 28 extended; 15 in this position the pliers 23 may be inserted into the manhole 11 of the covering casing 10 and the jaws 28 moved downwardly about the springs 15 until the three slots 29 of each jaw 28 span the spindles 13 and the seating of the springs in the depressed portions 30, intermediate said jaws, arrest further downward movement. This position of the jaws 28 is shown in Figs. 6 and 7, where it will be seen that the edges of the jaws do not come in contact with the spindles, but they 25 are held slightly above the latter by the end coils of the springs 15 which are of a greater gauge than the width of the margin 30. The three springs 15 may then be simultaneously compressed by moving the handles 30 24 to approach each other, a position illustrated in Fig. 4.

The jaws 28 approach each other in substantially a parallel movement which is caused by the followers 31 being held against 35 the diminishing curve of the moving cams 32 of the handles 24 as the latter are closed. The spring 33 tends to pull the followers toward each other which results in their constant engagement with the opposed cam surfaces 40 32.

I claim:—

1. In combination with a spring compression tool adapted to embrace the springs carried by the pedal spindles of a transmission case, of a flexible member having one 45 end attachably secured to said tool, and a locking member attachably secured to the opposite end of said flexible member and provided to engage said pedal spindles, whereby the latter may be locked against movement.

2. In combination with a spring compression tool adapted to embrace the springs carried by the pedal spindles of a transmission case, said tool comprising pivotally connected handle members, and clamping jaws pivoted to one end of each of said handle members, of means whereby said jaws may be actuated to approach each other in substantially parallel alignment, a flexible connecting member attached at one end to said tool, and a locking device attached to the opposite end of said flexible member and provided to engage said pedal spindles to 60 temporarily arrest movement of the latter.

3. In combination with a spring compression tool of the character described, provided with two pivotally connected handle members, each of said handles having one of its ends provided with a clamping jaw, said 70 handle members having cam surfaces cooperating with a portion of said jaws whereby the latter may be moved to approach each other in a substantially parallel line, of a locking device adapted to engage parts of 75 a transmission control mechanism, whereby the latter may be rendered inoperative to permit the manipulation of said compression tool, and flexible connecting means attached at opposite ends thereof to said tool 80 and locking device.

4. In spring compression pliers of the character described, the combination with a flexible connecting member attached at one end to said pliers, of a pedal locking 85 tool secured to the opposite end of said connecting member and provided with a slot adjacent its central portion, a fixed seat carried at one end of said tool, and a swivel seat mounted in the opposite end thereof. 90

5. Spring compression pliers of the character described, comprising two pivotally connected handle members, opposed jaws carried on the ends of said handle members, cam provided on the outer edge of said 95 handle members adjacent their pivotal connection, followers disposed at one end of each of said jaws, and means adapted to hold said followers in engagement with said cams, whereby the approach of the handle members to each other will cause the jaws to approach each other in a substantially parallel plane, the free ends of said jaws being provided with slots, each of the latter being substantially opposite to the slot in the opposing jaw. 105

6. Spring compression pliers of the character described, comprising two pivotally connected handle members, opposed jaws carried on the ends of said handle members, 110 cams provided on the outer edge of said handle members adjacent their pivotal connection, followers disposed at one end of each of said jaws, means adapted to hold said followers in engagement with said cams, whereby the approach of the handle members to each other will cause the jaws to approach each other in a substantially parallel plane, each of said jaws being provided with slots in one end thereof, the said 115 slots having marginal depressions provided adjacent their edges and in opposite faces of the jaws, whereby the edges of said slots may be supported against engagement with certain parts closely adjacent their field of 120 movement.

7. In a tool for the purpose specified, the combination with a pair of pivotally interconnected jaws each having a cam surface at its outer edge adjacent the pivotal point 130

of the jaws, of clamping jaws pivoted to said first named jaws and having portions in engagement with said cam surfaces, and means for yieldingly holding said portions in engagement with said cam surfaces.

5. In a tool for the purpose specified, a

locking member having means for simultaneously locking a plurality of spindles against movement.

In testimony whereof I have affixed my 10
signature.

LOUIS ULLMAN.
